UNITED STATES PATENT OFFICE.

ABRAM SCHENCK BERGEN, OF HUNTINGTON, NEW YORK.

CARBURETER.

1,212,887.

Specification of Letters Patent.

Patented Jan. 16, 1917.

Application filed November 25, 1912. Serial No. 733,347.

To all whom it may concern:

Be it known that I, ABRAM SCHENCK BERGEN, a citizen of the United States, and a resident of Huntington, in the county of 5 Suffolk and State of New York, have invented new and useful Improvements in Carbureters, of which the following is a specification.

My invention relates to improvements in carbureters of the automatic type, and the objects of my invention are to provide a simple and efficient carbureter which will provide substantially a constant mixture of fuel and air through its entire range; to 15 provide ready means for varying the ratio between the quantity of fuel and the quantity of air, which ratio, when established, shall remain substantially constant throughout the range of the carbureter; to provide 20 means whereby the carbureter shall operate under a substantially constant vacuum; to provide means for automatically varying the effective area of the air and fuel intake ports to correspond with the demand for mixture upon the carbureter; to provide means whereby the float feed chamber may be adjusted to any desired position with relation to the mixing chamber; to provide 25 means whereby the throttle valve in the float chamber and its seat may be readily removed; and to provide means for accelerating the velocity of a portion of the air admitted to the mixing chamber for the 30 purpose of properly pulverizing the liquid fuel.

The other objects are pointed out in the specification and claims.

The essential features of my invention are pointed out in the specification and in 40 the appended claims.

I attain these objects by the mechanism illustrated in the accompanying drawings, in which—

Figure 1 is a perspective view of my carbureter; Fig. 2 is a plan view of the bottom of my invention; Fig. 3 is a sectional elevation on the line $x-x$ of Fig. 2; Fig. 4 is a sectional view on the line $t-t$ of Fig. 3; and Fig. 5 is a sectional view of a modification of my invention, showing the lower end of the mixing chamber and piston valve.

Similar numerals refer to similar parts throughout the several views.

My carbureter is provided with a float feed chamber 1, which is provided with a float 3, having a passage 3^a therethrough,

through which the stem 5 of the ball valve 4 passes. To the upper end of the stem 5 is attached an adjustable stop 5^a.

2 is a removable cover, in which is the usual opening 2^a for the admission of air to the chamber. A removable guide 6 is secured in the bottom of the float feed chamber 1, which is provided with a valve seat 7, and in the lower end of the guide 6 is secured a pipe 8, by which liquid fuel, such as gasoline, is supplied to the chamber 1, the flow of fuel being cut off when the fuel has risen to a sufficient height in the chamber 1 to force the valve 4 against the seat 7. 70 The guide 6 being removable, the valve 4 may be conveniently ground into its seat by removing the guide 6 and the float 3 and valve 4 from the chamber 1. The chamber 1 is also provided with a drain-cock 9 in order that any water or other foreign substance which may accumulate in the bottom of the carbureter may be drawn off. A passage 10, located at a distance above the bottom of the chamber 1, connects with a spray nozzle 11, which is centrally located in the mixing chamber 12, which is cylindrical in form and is mounted upon a base 13, which is shown as cast integrally with the chamber 1. The mixing chamber 12 is secured to the base 13 by studs 13^a, which pass through a collar 13^b and the base 13 and the nuts 13^c and the split ring 13^d, which is sprung into a groove 13^e near the lower end of the cylinder 12. The base 13 is provided with air intake openings 14 and a disk 15 with openings 16 is secured in place against the lower face of the base 13 by a nut 17. The disk 15 acts as a shutter, which may be rotated for the purpose of opening and closing the air ports in the base 13. This disk is provided with an arm 18 and the stud 19, which may be secured in any one of the series of the openings in the arm 20. The base 13 is also provided with a slot 20^a, 100 which registers with the stud 19, and by adjusting the stud 19 in the openings in the arm 20 the movement of the arm 18 and the rotation of the disk may be limited. In order to maintain the disk 15 in the desired position, I have provided a spring 21, which tends to force the stud 19 to the limit of its movement in the slot 20^a in the direction of the arrow, the movement in this direction tending to uncover the air 110 ports in the base 13. By means of the cable 22, the shutter may be rotated in the oppo-

site direction so as to partially or wholly close the air ports 14. This is for the purpose of enabling the operator to enrich the mixture with fuel just before the engine is stopped in order that it may be readily started from the spark and without cranking. The cylindrical chamber 12 is provided with a number of air intake openings 23, preferably rectangular in form, the total capacity of such air intake openings being greater than the capacity of the outlet neck 24 of the chamber 12, which is provided with a flange 25, to be secured to the intake pipe of an internal combustion engine.

26 is a butterfly throttle valve of the usual type. In the chamber 12 is mounted a piston valve 27, which normally rests in the position shown in Fig. 3. The valve 27 is provided with ports 28, which, as shown in the drawing, are four in number, whereas the ports in the chamber are seven in number. This enables me to dispense with any guide for piston valve 27, as when the piston 25 is raised it may be rotated in the cylinder without affecting the area of the air intake openings uncovered by the piston.

One criterion that may be applied in determining the number, form, and arrangement of the ports in the respective members to maintain the area of the air intake openings uncovered by the piston, may be stated as follows: Divide the circumference between the two members into as many equal parts as the product of the number of ports in the piston multiplied by the number of ports in the casing, the ports in each member being equidistant from each other and of equal width and form, and the partition walls in one member being of a width at least equal to one of the equal divisions of the said circumference. The number of ports in one member must be greater than the number of ports in the other member, and when the number of ports in one member is a multiple of the number of ports in the other member, the width of the walls between the ports in the member having the lesser number of ports must be at least 50 equal to that portion of the circumference which is equal to the divisions obtained by dividing the circumference into as many equal parts as the number of ports in the member having the largest number of ports.

55 The piston is also provided with a downwardly flaring tube 29, through which all of the air admitted through the ports 16 must pass in close proximity to the spray nozzle so as to cause the air which passes 60 by the spray nozzle, even when but a small amount of mixture is demanded from the carbureter, to travel past the spray nozzle at a sufficient speed to properly pulverize the liquid fuel. The area of the fuel intake 65 opening is determined by the tapered needle

valve 30, which extends down into the spray nozzle. The needle 30 is mounted in a yoke 31, supported on the piston 27, and is adjustable as to height by means of the nuts 32 and 33. The needle 30 is so tapered that as the piston 27 rises and falls carrying with it the needle valve 20, the effective area of the fuel intake opening will correspond with the combined effective area of the ports 14 and of the air ports 23, as they are covered and uncovered by the piston 27.

I have also provided a stop shoulder 34, which limits the upward movement of the piston, and I have also provided a tubular collar 35, which may be rotated about the chamber 12 so as to increase or diminish the width of the air openings 23, thus providing means for adjusting the amount of air which is admitted to the chamber 12 as against the amount of fuel which is submitted to it through the spray nozzle 11. When the tubular collar 35 has been properly adjusted it may be secured in position by the screw 35.

I have also provided at the upper end of the mixing chamber a water jacket 38 of the usual construction, to which heated water from the water jacket of the engine is admitted through the pipe 39 and discharged through the pipe 40.

In Fig. 5, I have shown a modification of my invention, in which a stationary hour-glass-shaped tube 36 is mounted on the base 13 so as to surround the spray nozzle 11. The upper end of the spray nozzle being located in the constricted portion of the tube 36. Mounted in the central opening through the piston valve 27 is a downwardly flaring tube 37, the lower end of which in all positions of the valve 27 will surround the upper end of the tube 36. By this construction, I am able to lead the air which enters through the openings in the base 13 past the spray nozzle at the highest possible speed so as to properly pulverize the liquid fuel, even when but a small demand for mixture is being made upon the carbureter. The tubes 36 and 37 are so constructed as to be at all times out of contact, thereby avoiding any danger of the valve 27 binding and failing to act through contact of the tube 37 with the tube 36, and rendering it possible to always maintain the upper end of the spray nozzle in the most constricted portion of the tube 36, where the inflowing air will contact with the liquid fuel at the maximum air velocity.

In the operation of my carbureter, I prefer to so adjust the needle valve 30 and the shutter 15 that the quantity of mixture which will be supplied by the carbureter without lifting the valve 27 will be just sufficient to run the engine idle at a slow speed. When this has been accomplished through the adjustment of the stud 19 the mixture

may be readily adjusted for all speeds and loads by the rotation of the collar 85.

In practice, I have found that these adjustments are readily and accurately made 5 and that under all conditions the air travel past the spray nozzle is sufficient to properly pulverize the fuel, resulting in greater flexibility of the motor, increased power and a very considerable reduction in the amount 10 of fuel consumed to produce a given result.

By the construction shown, the cylinder 12 may be rotated on the base 13 to any desired position, so that when the carbureter is attached the float feed chamber may be located 15 in any desired position with reference to the engine.

Having described my invention, what I claim as new and desire to secure by Letters Patent is:

20 1. A carbureter comprising in combination, a cylindrical mixing chamber having air ports in its side wall, an inverted piston valve mounted therein and adapted to be actuated by the suction of the engine, said 25 piston valve having air ports in its side wall adapted to variably register with those in the wall of the mixing chamber when the piston valve is elevated, an air nozzle centrally mounted in said piston valve and discharging 30 into said mixing chamber, said air nozzle having air admission ports in communication therewith, a spray nozzle surrounded by and discharging into said air nozzle, and a needle valve carried by said piston valve 35 and operating in the spray nozzle.

2. A carbureter comprising in combination, a chamber having air ports in its wall, a hollow piston valve slidably fitting the inner side of the chamber and having air 40 ports variably registering with those in the

wall of the latter, said hollow piston valve carrying therewith an internally arranged air nozzle in communication with the outer air, a spray nozzle in communication with the fuel supply and extending into said air 45 nozzle, and a needle valve carried by the piston valve and operating in the spray nozzle.

3. A carbureter comprising in combination, a chamber having air ports in its wall, 50 and in its bottom, a hollow piston valve slidably registering inside of the chamber and having lateral air ports, said hollow piston valve carrying therein an internally arranged air nozzle in communication with 55 the bottom air ports and presenting a piston surface over said bottom air ports, a spray nozzle extending into the air nozzle, and a needle valve carried by the piston valve and operating in the spray nozzle. 60

4. A carbureter comprising in combination a float feed chamber provided with a base, a cylindrical mixing chamber provided with a flange at its upper end, adapted to be secured to the intake pipe of an explosive 65 engine, a circumferential groove near the lower end of said mixing chamber, a divided ring adapted to fit into said groove, a collar adapted to fit around said mixing chamber and contact with said divided ring when inserted in said groove, and means for securing said collar to said base. 70

Signed at New York city in the county of New York and State of New York, this 14th day of November, A. D. 1912.
